UNITED STATES PATENT OFFICE.

GEORGE A. ICKES, OF ALTOONA, PENNSYLVANIA, ASSIGNOR, BY MESNE ASSIGNMENTS,
TO SIDMA E. ICKES, OF ALTOONA, PENNSYLVANIA.

REFRIGERATOR.

994,163.

Specification of Letters Patent. Patented June 6, 1911.

Application filed October 14, 1909. Serial No. 522,645.

To all whom it may concern:

Be it known that I, GEORGE A. ICKES, M. D., a citizen of the United States, residing at Altoona, in the county of Blair and State of Pennsylvania, have invented certain new and useful Improvements in Refrigerators, of which the following is a specification.

This invention contemplates a sanitary drinking cold water supply and refrigerating system, by using pipes to distribute cold water through a refrigerator plant, discharging cold water at different levels and temperature and distributing cold water to all parts of a refrigerator or ice box.

A general object of the invention is to provide means whereby not only a cheap grade of ice may be used with perfect safety from a sanitary standpoint, but that perfect sanitary conditions may be maintained throughout the interior of the refrigerator by the system of drainage that I propose to use and describe as a part of this specification.

The essential features of this invention are necessarily susceptible to a wide range of structural modification without departing from the spirit thereof, but a preferred and practical embodiment is shown in the accompanying drawings, in which—

Figure 1 is a general sectional perspective view of the entire apparatus. Fig. 2 is a sectional view of the drinking water valve, which I employ to secure the objects set forth, together with a view of the drinking cup, stand and drain cup. Fig. 3 is a front view of the valve device shown in Fig. 2. Fig. 4 is a detail of the valve operating handle.

Like references designate corresponding parts in the several figures of the drawings.

Referring to the accompanying drawings the number 10 designates the inlet pipe connected with the city water supply, fitted with a stop cock 11, preferably located in the cellar or basement of the building wherein this device is installed. Above the cut off valve or stop cock 11 the water passes through the pipe section 12 into a charcoal or equivalent filtering device 13. This filter 13 is shown outside the refrigerator in order to show the pipe lines more clearly, but it is the purpose of the inventor to place this device inside the refrigerator when the same permits of such installation. After city water

has left the filter 13 it passes through the pipe section 14 into the coil of piping 14^a, arranged within and about the ice box 15 of the refrigerator casing 16. This refrigerator casing is provided with the usual lid 17 and the trays or shelves 18, having suitable supporting elements associated therewith. The coil of piping within the ice box or chamber also includes a section lying at the bottom of the ice chamber, and from this bottom coil the water successively passes through the separate shelf coils 19 and 20 arranged within the separate refrigerator compartments above the shelves therein, so as to expose a maximum surface of piping. The coil at the bottom of the piping system is provided with a valved draw off connection 21, to permit the system to be drained.

The upper, intermediate and lower pipe coils are connected to a three way draw off valve 22, through the pipe sections 23, 24 and 25 respectively. The valve 22 is provided with a casing 26, and valve proper 27 and an operating handle 28 which is provided with a projection 29 on its lower edge designed to register with suitable indicating marks or points, on the face of the valve disk 31. The valve 27 is constructed to fit in a casing 26, and is capable of being rotated by the operating handle 28 to various predetermined positions, each position permitting communication between one system of coils and the spigot 32; from which drinking water is discharged into the drinking cup 33, the temperature of the drinking water which will be obtained for each definite position being marked on the disk 31 of the valve body.

If it is found that the water in the bottom coil of the ice box is too cold for drinking purposes, provision is made at 34 whereby a section can connect this tee 34 to the center nipple 24 of the operating valve, thereby getting water at a temperature slightly higher than that obtained in the bottom of the ice box.

The valve as illustrated in Fig. 2 shows the position of the handle 28 when the spigot is closed and the circulation being in progress. When the handle is moved down 45° water will be drawn from the bottom coil in the refrigerator whose contents are higher in temperature than any other coil. On movement of the operating handle down through an arc of 90° water from the mid-

idle coil of the ice box or chamber will be delivered to the drinking cup 33 through the spigot 32, and on movement of 45° upward water will be drawn from the top of the 5 coil in the ice box.

In order to complete the system of perfect sanitation I have installed a spigot drain cup 35 which connects through a pipe section 36 to a drain tank or box 37 located 10 beneath the refrigerator and connected with a trap 38 that leads to the sewer. The bottom coil 20 is provided with a stop cock 21 and drain section 40 which enables the operator to drain the entire system. The 15 pans and trays are also provided with a system of drains which communicates through a pipe section 41 to the drain box which is connected to the sewer.

It will be seen without further detailed 20 description that the system is perfectly sanitary, allowing the drinking water to be drawn at a number of temperatures, and providing means whereby the entire system may be flushed and the impurities washed 25 into the sewer beneath.

By this system of construction, we put the laws of hydrostatic motion into force and operation, thereby establishing a refrigerating system as well as a sanitary cold water 30 supply. This system is applicable to any and all cold storage and refrigeration systems such as meat markets, produce or meat

cars in transit, cold storage plants or in vessels at sea.

I claim:

1. In a refrigerator, the combination with 35 the casing, of a plurality of communicating pipe coils arranged within different compartments of the casing, upper intermediate and lower draw off pipe sections connected 40 with upper intermediate and lower pipe coils, and a three-way drinking water valve device associated with said several draw off pipe sections and comprising means for individually establishing communication with 45 any one of the same at a time.

2. In a refrigerator, a casing having a plurality of compartments, water circulating pipe coils in communication with each other and respectively arranged in the separate compartments, a multi-way valve device having draw off connections with different coils in the system, a common drain tank, and means for draining the pipe coils into the said tank, and means for carrying 50 the drainage from said valve device into said tank.

In testimony whereof I hereunto affix my signature in the presence of two witnesses.

GEORGE A. ICKES.
